UNITED STATES PATENT OFFICE.

THOMAS WILLIAMSON, OF CLEVELAND, OHIO, ASSIGNOR OF ONE-HALF TO
JOHN GOEPPINGER, OF YOUNGSTOWN, OHIO.

ROLLING-MILL.

SPECIFICATION forming part of Letters Patent No. 690,382, dated December 31, 1901.

Application filed July 12, 1901. Serial No. 68,078. (No model.)

To all whom it may concern:

Be it known that I, THOMAS WILLIAMSON, a citizen of the United States, residing at Cleveland, in the county of Cuyahoga and State of Ohio, have invented certain new and useful Improvements in Rolling-Mills, of which the following is a specification.

My invention relates to the art of metal-rolling in general and to the improvement of mills employed in this connection for shaping and rolling from the bloom or billet bars, such as grooved street-rails. These mills as ordinarily constructed comprise a set of reversing-engines coupled to a train of pinions, in turn connected to a set of roughing or shaping rolls, and finally a connected set of finishing-rolls, in which latter reside the novel features of my present invention.

More particularly stated my invention contemplates a peculiar and novel arrangement of finishing-rolls, which, in addition to a pair of horizontal rolls, includes a coöperating vertical roll, all three positively driven in either direction from the finishing-train by suitable couplings and connections, as will hereinafter more fully appear.

Another and no less important feature of invention resides in a power-press and its actuating mechanism for setting and shaping the end of a bar or rail preparatory to entering the last finishing-pass between the aforesaid horizontal and vertical rolls.

Still other features of improvement consist in the general arrangement and combination of rolls and their supporting-housings, whereby the outside vertical roll in particular may be readily removed, repaired, or replaced should occasion for so doing arise.

Among its objects and advantages my invention contemplates and effects a material increase in the general efficiency of mills, as also their durability. It obviates the necessity of a dummy pass, and consequently saves the time and labor which would otherwise be required to make such pass. It presents the bar or rail to the final finishing-pass at a higher degree of heat than would be the case were a dummy pass used, which results in a better rolled product with less wear and tear upon the mill and reduces to a minimum breakage of the rolls themselves.

The invention will be hereinafter described, and particularly pointed out in the claims following.

In the accompanying drawings, which form part of this specification, and whereon corresponding letters of reference indicate same parts in the several views, Figure 1 is a side elevation of a set of finishing-rolls embodying my improvements. Fig. 2 is an end view of my invention. Fig. 3 is a detail fragmentary view illustrating a supporting-bracket and a portion of the upper toggle-arms for actuating the bending-press. Fig. 4 is a top plan view of an oscillating cylinder for operating the toggle, and Fig. 5 is a corresponding view of the bending-press with a section of rail in the course of bending.

Reference being had to the drawings and letters thereon, A A' indicate the vertical members of a mill-housing, wherein are suitably journaled horizontal and vertical rolls B, B', and C, respectively, all driven at uniform speed from a common source of power. The horizontal rolls B B' project through housing A', where, in conjunction with the flanged vertical roll C, they constitute the final pass of the train, while, as clearly shown by Fig. 1, said vertical roll C is positively driven from the finishing-rolls in either direction by the agency of pinions D D, a shaft E, journaled above in housing A A', and miter or bevel tooth gears F, which transfer the horizontal motion to a vertical. In this connection it should be particularly noted that all movable parts thus far described are rendered easily adjustable by means of outside adjustable bearings, such as a, for convenience of removal or compensation for ordinary wear and tear, and the vertical roll C is thus made adjustable with relation to horizontal rolls B B' for the purpose of applying pressure to shape and reduce a bar or rail in course of finishing instead of serving merely in the capacity of a guide or friction roller.

G indicates an upstanding block or anvil keyed or otherwise firmly secured to the base of the mill or housing A', the face whereof is configured to receive one side of a bar or rail to be operated upon, while at b upon said block is hinged a power-press H, the inner working face whereof is substantially a counterpart of

the rail-groove in block G aforesaid, while its extreme outer edge terminates in a down-turned flange or lip *c* for purposes which will later appear. To the upper portion of housing *A'* is bolted a projecting bracket *I*, mounting a stud-pin *d*, from which latter depend, in pivotal relation, upper and lower toggle-arms *e f*, respectively, each arranged in duplicate pairs for purposes of strength and convenience of assembling. Pivotedly mounted upon another bracket similarly secured to the side of housing *A'* is an oscillating cylinder or engine *J*, provided with a piston *g*, operated by steam or other fluid pressure and itself pivotally connected to the toggle-arms *e f* for the purpose of quickly and forcibly throwing same when required, as will appear in connection with a statement of operation to follow.

The foregoing being a general description 20 of my invention in its preferred form of construction, it should be particularly noted that I by no means limit myself to the precise construction and arrangement of parts herein shown and described. On the contrary, many 25 changes and modifications will readily suggest themselves to those skilled in the art to which these improvements relate which are entirely within the spirit of my present invention, and for all such I claim the protection 30 of Letters Patent.

Having thus described the leading features of my invention, its use and operation may be stated as follows: A highly-heated bar or rail having advanced regularly in the process 35 of shaping from a bloom or billet to the finishing-point is taken from the next-to last pass of the finishing-roll, as indicated upon Fig. 1 by the letter *X*, and inverted and placed flange up upon the grooved surface of block or 40 anvil *G* preparatory to entering the final or finishing pass formed by a combination of the rolls *B*, *B'*, and *C*. At this instant steam or other motive fluid is admitted to cylinder *J* by means of a throttle-valve (not shown) under control of the operator, whereupon toggle-arms *e f* are driven outward and press *H* descends forcibly, its advance lip *c* serving to instantly and effectually break down or bend the previously-upstanding rail-flange, as indicated at *y*, Fig. 2, thus adapting it for immediate entrance between rolls *B*, *B'*, and *C* in alignment therewith, from which it emerges the complete and finished product of the mill.

Having thus described my invention, its 55 use, and purposes, what I claim, and desire to secure by Letters Patent, is—

1. In a rolling-mill the combination with a

set of finishing-rolls and their housing, of a power-press pivotally supported upon the housing for shaping the advance end of a rail 60 preparatory to entering the final pass, substantially as described.

2. In a rolling-mill the combination with a set of finishing-rolls and their housing, of a power-press pivotally supported upon the 65 housing for shaping the advance end of a rail preparatory to entering the final pass, and a toggle-lever for actuating said press, substantially as described.

3. In a rolling-mill the combination with a 70 set of finishing-rolls and their housing, of a power-press pivotally supported upon the housing for shaping the advance end of a rail preparatory to entering the final pass, a toggle-lever for actuating said press, and a fluid-pressure engine for throwing said toggle-lever, substantially as described.

4. In a rolling-mill the combination with a suitable housing, of a power-press pivotally supported upon the housing for shaping the 75 advance end of a rail, a set of finishing-rolls comprising a pair of horizontal and one vertical roll, the latter coöperating with said horizontal rolls to form the final pass, substantially as described.

5. In a rolling-mill; the combination with a suitable housing, of a set of finishing-rolls, comprising a set of horizontal rolls projecting through the housing, and one vertical roll adjacent to the projecting end of said horizontal rolls, and coöperating therewith to form the final pass, all of said rolls being driven from a common source of power, a power-press pivotally supported upon said housing, for shaping the advance end of a rail 90 preparatory to entering the final pass, and a toggle-lever for actuating said press, substantially as described.

6. In a rolling-mill, the combination with a suitable housing, of a set of finishing-rolls, comprising a pair of horizontal rolls and one vertical roll, supported in a housing common to all, and all driven from a common source of power, a power-press pivotally supported upon said housing, for shaping the advance 100 end of a rail preparatory to entering the final pass, and a toggle-lever for actuating said press, substantially as described.

In testimony whereof I subscribe my signature in presence of two witnesses.

THOMAS WILLIAMSON.
